UNITED STATES PATENT OFFICE.

EDMOND W. T. RICHMOND, OF ROMFORD, ENGLAND.

DESIGN FOR A GAS-STOVE.

SPECIFICATION forming part of Design No. 33,876, dated January 8, 1901.

Application filed December 11, 1900. Serial No. 39,556. Term of patent 7 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design consist of the annular body A, having an upwardly-sloping periphery a, a series of wings B, extending above the body and into the annular space within the body and having serrated

upper edges, and the handle C, projecting laterally from the body portion. The body portion and the handle are ornamented by a series of parallel vertically-arranged grooves, ²⁰ and the body portion is ornamented on its top by an annular series of holes b.

I claim—

The design for a gas-stove, substantially as herein shown and described. ²⁵

In testimony whereof I have hereunto subscribed my name.

EDMOND W. T. RICHMOND.
